UNITED STATES PATENT OFFICE.

CHRISTIAN AALBORG, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-BREAKER.

1,099,332.

Specification of Letters Patent. Patented June 9, 1914.

Application filed July 3, 1905. Serial No. 268,266.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Circuit-Breakers, of which the following is a specification.

My invention relates to circuit-breakers, and it has for its object to provide a hand-operated and automatically-released circuit-breaker with means for preventing the holding of the breaker in its closed position under overload or other predetermined conditions, that shall be simple in construction and effective in operation and that shall not interfere with the normal operation of the breaker.

The circuit breaker of my invention is provided with a special construction which prevents it from remaining in its closed position under overload conditions, even though a retaining force be applied to the operating handle, so that protection of the circuit and its translating devices is insured and is dependent only upon the automatic tripping device.

A further advantage of the breaker of my invention lies in the fact that it may be hand-operated under normal conditions to open and close the circuit, at the will of the operator.

In the accompanying drawings, Figure 1 is a side elevation and Fig. 2 a front elevation of a circuit-breaker constructed in accordance with my invention and shown in closed position. Fig. 3 is a side elevation of the circuit-breaker shown in Figs. 1 and 2, the movable member being shown in its open position.

Although my invention is shown only in connection with a breaker which is automatically released under overload conditions, it may be applied to breakers which are adapted for operation under other predetermined conditions.

The principal stationary parts of the circuit-breaker illustrated are a non-conducting slab or panel 1, a supporting bracket 2, a main contact terminal block 3, an arc-breaking terminal block 4 and a conducting strip or plate 5 between the blocks 3 and 4. The bracket 2 comprises a pair of substantially parallel plates 2^a that are secured to the panel 1 by bolts 1^a and project outwardly

therefrom. Pins 9, 15 and 25 are so supported by the plates 2^a that they are parallel to the plane of the slab 1 and serve as axes for the movable parts of the breaker. A two-part lever 8 is pivotally mounted near one end 60 on the pin 9 and is provided with a pin 8^a at its outer end which ties the two parts of the lever together and supports main and auxiliary contact-bearing members 7 and 11 that are mounted thereon. The member 7 is 65 prevented from rotating about the pin 8^a as an axis and the member 11 is limited in its rotation about the same axis by a pin 13 which passes through a projection for the former and through a relatively large hole 70 12 in the latter. A spring 11^a is interposed between the members 7 and 11 in order to tilt the auxiliary contact-bearing members forward when the breaker is open.

An operating handle 14 is attached to a 75 double forked operating lever 14^b which is pivotally mounted on studs or rivets 15 by which its outer prongs are attached to the outer extremities of the bracket plate 2^a. The inner prongs of the lever 14^b are 80 materially longer than the outer prongs and are connected with the pin 8^a at the extremity of the lever 8 by means of a link 16 and a pair of shorter parallel links 17 and 18, which are constructed to act as a single connecting link under normal conditions and to assume the position shown in Fig. 1 when the breaker is closed and that shown in Fig. 3 when the breaker is open.

A laminated current-carrying contact 90 member 6 is attached to the member 7 and is resilient by reason of its structure so that it will compensate for a certain wear which occurs on the contact surface.

An auxiliary contact member 10 which 95 may be constructed of carbon or other suitable material is adapted to coöperate with the stationary arc breaking contact member 4. A conducting plate 10^a is attached to the member 10 by means of a hollow rivet or 100 stud 10^b and is supported, adjustably attached, to the member 11 by side projections 11^b which extend loosely through holes 11^c in two parallel side plates of the member 11. A spring 10^c is interposed between the members 10 and 11 and is located within the hollow stud or rivet 10^b. By this means the movable auxiliary contact member will seat itself when it engages the stationary member 4. 110

The links 17 and 18 are connected to the extremity of the handle lever 14 at one end by a pin 14^a and at the other end are connected to substantially the middle point of the link 16 by a pin 16^a. The free end of the link 16 is provided with a projection 19, that may be engaged by a portion of the tripping mechanism; and with a projection 20 which normally engages the connecting pin 14^a by which the links 17 and 18 are attached to the operating lever 14.

The tripping mechanism comprises a frame 21, upon which is adjustably mounted a weight 22 and to which a U-shaped armature 23 of magnetizable material is attached. The frame 21 is suspended from a tripping lever 24 that is rotatably mounted upon a pin or rod 25 with which the supporting bracket 2 is provided. A magnetizing winding 26 is coiled about a magnetizable core 27, which surrounds the shaft 9.

The inner end of the coil or spiral 26 is electrically connected with the side plates 2^a of the bracket by means of the bushing or core 27 and its outer end is connected directly (as shown in Fig. 1), to a main terminal stud 7^a of the breaker. It will be observed that when the breaker is closed an electric circuit may be established from stationary contact member 3 through movable member 6, shunt 6^a, bracket plates 2^a, bushing 27 and the coil 26 to terminal 7^a. When the current flowing through the circuit exceeds a predetermined amount, the armature 23 is attracted by the core 27 and the free end of the tripping lever 24 is moved into engagement with the projection 19 of the connecting link 16. When this occurs the breaker is thrown, by a spring 28, to the position indicated by broken lines in Fig. 3. When the breaker is closed, it is retained in this position normally by a projection 29 which is attached to the handle lever and engages the pin 30 on the bracket 2, since the pivot pins 14^a and 16^a are substantially in the same straight line. When the breaker is operated by hand to open the circuit, the lever 16 and the connecting links 17 and 18 retain the same relative positions, while the joint between the links 17 and 18 and the handle lever 14^b is broken to form an acute angle, as shown in full lines in Fig. 3.

When the free end of the tripping lever 24 is brought into engagement with the projection 19 of the link 16, the joint between the connecting links 17 and 18 and the link 16 is broken, as well as the joint between the links 17 and 18 and the handle lever 14^b, and the breaker assumes the position indicated by broken lines in Fig. 3. It is obvious that if the handle is held in the position shown in Fig. 1, it will not prevent the opening of the circuit by the tripping mechanism.

I desire and intend to include within the scope of my invention all variations from

the specific details shown and described that do not involve material changes in mode of operation or result.

I claim as my invention:

1. In a circuit-breaker, the combination with a movable switch member, an operating lever fulcrumed at a point intermediate its ends, and jointed links which connect one end of the lever to the switch member and are movable into self sustaining alignment, solely by the operation of said lever, to maintain said member in circuit-closing position, of tripping means acting directly upon one of said links to release said switch member independently of the operating lever. 70

2. In a circuit-breaker, the combination with a movable switch member, an operating lever fulcrumed at an intermediate point in its length, and a connecting and locking means between the switch member and one end of the operating lever, which comprises a relatively long link and a pair of short links, of means for engaging the free end of the long link to open the circuit-breaker independently of the operating lever. 80

3. In a circuit-breaker, the combination with a movable switch member, an operating lever fulcrumed at an intermediate point in its length, a relatively long link connected to the switch member and a pair of short links between one end of the operating lever and an intermediate point in the long link, of an automatic tripping means which is dependent upon predetermined circuit conditions for engaging the free end of the long link 90 to open the circuit-breaker independently of the operating lever. 95

4. In a circuit-breaker, the combination with a movable switch member, an operating lever fulcrumed at an intermediate point in its length, a relatively long link connected to the switch member and a pair of short links between one end of the operating lever and an intermediate point in the long link, of an electro-magnet which is responsive to predetermined conditions in the circuit, and an armature for tripping said links to open the circuit-breaker independently of the operating lever. 100

5. In a circuit-breaker, the combination with a stationary contact member, a movable member provided with a laminated contact terminal and a resiliently supported arc-breaking contact terminal, an operating handle and an automatic tripping mechanism, 115 of means for connecting the movable contact member and the operating handle lever together, said means comprising a long link having one end pivotally connected to the movable contact member and a pair of parallel links pin-connected to said long link substantially at its middle point and also pin-connected to one end of the operating handle lever. 120

6. In a circuit-breaker, the combination 130

with a stationary contact member and a supporting bracket, a movable contact member, a tripping device and an operating handle pivotally mounted upon said bracket, of 5 means for mechanically connecting the movable contact member and the operating handle together, said means comprising a long link which is pin-connected at one end to the movable contact member and a pair of parallel links which are pivotally mounted upon one end of the operating handle and are pin-connected to said long link substantially at its middle point. 10

7. In a circuit breaker, the combination 15 with a movable switch member, an operating

lever, and jointed links which connect the lever to the switch member and are movable into self-sustaining alignment, solely by the operation of said lever, to maintain said member in circuit closing position, of tripping means acting directly upon one of said links to release said switch member independently of the operating lever. 20

In testimony whereof, I have hereunto subscribed my name this 29th day of June, 25 1903.

CHRISTIAN AALBORG.
